APPLICATOR FOR POLISHING COMPOUNDS
AND LUBRICANTSWilliam Howard Chandler, Shaker Heights,
Ohio, assignor to The Chandler Chemical Com-
pany, Cleveland, Ohio, a corporation of Ohio

Application June 18, 1934, Serial No. 731,120

12 Claims. (Cl. 51—263)

This invention relates to an applicator for applying lubricants, polishing compounds and soft plastic materials of low viscosity to grinding and polishing wheels, belts and like high speed finishing surfaces. For the purpose of illustration my invention will be described particularly in relation to the application of tallow to finishing wheels, wherein the problems to be solved by the invention and the solutions thereof will be readily apparent, the use thereof in connection with other polishing compounds and lubricants on moving finishing surfaces being readily apparent from the specific example described.

In the fine grinding or polishing of articles it is necessary that a suitable film of lubricant be maintained on the surface of the wheel or polishing means. Tallow is one of the cheaper and more satisfactory materials for this purpose as it can be removed easily from the article by a weak alkali bath and water rinse. However, it has such a low melting point and low viscosity that it is very difficult to apply onto the moving wheel as it becomes soft and semi-fluid under the slight heat therefrom and collapses so that it cannot be held firmly against the wheel. In order to raise the melting point of the tallow, stearic acid, paraffine and the like have been mixed with the tallow, forming therewith a homogeneous mass of sufficiently high melting point and rigidity to be pressed and held against the wheel occasionally without collapsing thus causing enough tallow to be spread and retained on the wheel to produce the desired coating.

These methods, however, have serious objections. The loss of tallow is quite pronounced, a large proportion flying off from the wheel and mass during application due to both centrifugal force and the semi-fluid state of the tallow. Further, the stearic acid is relatively expensive and neither it nor paraffine have any lubricating effect. The stearic acid and paraffine adhere to the wheel and, of course, are transferred onto the article being polished or finished. To remove the paraffine from the article is much more difficult than removal of the compound or lubricant. In case the article is to be plated, it must be perfectly clean and free from all such foreign substances, as their presence on the article very deleteriously affects the plating operation.

One of the principal objects of the present invention is to provide an applicator by which oils, soft lubricants, polishing compounds and plastic materials having low melting points and viscosity may be applied efficiently and easily to the mov-

ing finishing surface without material loss of the lubricant or compound so applied.

Another object is to effect a more even distribution of the applied material over the finishing surface and to reduce splattering and loss of the material.

Still another object is to provide an applicator in which the material is stored and ready for use at all time and which is in a form which may readily be grasped in the hand of the operator and forced against the moving surface of the wheel.

More specific objects are to provide an applicator of this character which is reinforced against radial and axial collapse even when used in connection with a very soft plastic or fluid material to be applied, which will be worn away readily by the action of the wheel as the material contained therein is applied, and which is composed of a material which may readily be removed from the article on which the wheel has operated by the same bath and method that will remove the lubricant or material applied.

Other objects and advantages will become apparent from the following specification in which reference is made to the drawing, wherein

Fig. 1 is a side elevation illustrating a form of applicator embodying the principles of the present invention and the manner in which used;

Fig. 2 is an enlarged side elevation of the applicator, part thereof being shown in section for clearness in illustration;

Fig. 3 is a cross sectional view of the applicator taken on a plane indicated by the line 3—3 in Fig. 2; and

Fig. 4 is a cross sectional view of a modified form of applicator.

The applicator comprises generally a tubular casing 1, which is preferably of sufficient rigidity to be self-supporting and within which is a reinforcing and retaining core designated generally at 2. The core 2 is cellular in construction, the cells thereof being filled with and retaining the lubricant or material 3 to be applied to the moving surface of the wheel or other moving polishing surface.

In the form illustrated, the core is composed of a spirally wound corrugated paper of the type having a corrugated sheet 4, to one face of which, along the crests of the corrugations, is secured a backing sheet 5 to retain the corrugations in shape. The resultant sheet is preferably wound spirally, with the backing sheet 5 outwardly so that the wall portions of adjacent turns of the

sheet 5 are spaced from each other to form a spirally laminated core not only by the material therebetween but also by the corrugations parallel to the axis of the casing so as to form a plurality of resultant cells or pipes 6, which are substantially discommunicated from each other and which extend longitudinally through the resultant applicator.

These pipes are filled with the lubricant or soft, plastic material to be applied, preferably by pouring it in liquid state, into the ends thereof so that it may flow down to the bottom of the pipes and be retained thereby, whereupon additional material is added until the applicator is entirely filled.

The reinforcing and retaining core 2 is preferably self-supporting, as shown, and held by friction, gluing or otherwise within the casing 1. Thus the casing is reinforced both radially and axially. Both the casing and the core are preferably of a fibrous or absorbent material which may be permeated readily by the oil, lubricant, or material to be applied thereby, so that such material is firmly held by the core and assists in swelling the core and firmly interlocking it with the casing.

If desired, instead of the casing 1, the outer layer of the sheet 5 may form the casing, but this is usually not as satisfactory as it does not have as great rigidity.

The applicator with the material therein is forced endwise against the finishing surface on which the material is to be applied, as illustrated in Fig. 1. The applicator itself is of material of a characteristic which will be removed or worn away gradually and readily by the action of the wheel. Consequently, the end of the applicator quickly assumes snug engagement with the wheel for the entire diameter of the applicator.

The heat from the wheel tends to melt or reduce the viscosity of the material contained in the applicator but it cannot affect any great portion thereof so that the portion will move as a mass, due to the retaining and heat insulating effect of the cells or pipes. Further, heating of the material in that portion of the applicator actually engaging the wheel does not result in heating appreciably adjacent material in the applicator because of the cell walls. Again, the cell walls and the casing wall hold the material against the face of the wheel so that a uniform light film thereof is applied and spread thereonto. Furthermore, any appreciable mass of the material is prevented from flowing or tearing loose and being thrown off by the wheel, due to the fact that the core and casing material retain it within the limits of the end of the applicator. Thus much more of the material is actually applied efficiently with a resultant saving in the amount required.

In Fig. 4, a slightly modified form of applicator is illustrated, in which the corrugated paper for the core, instead of being spirally wound, is cut or folded into parallel strips, placed face to face, thus providing a core having parallel laminations rather than spiral laminations.

It is apparent from the foregoing description that an applicator of the character described may be utilized for applying substantially any material either solid or liquid to the finishing surface of the wheel while the surface is in motion and that the same is economical both as to manufacture and use.

Having thus described my invention,

I claim:

1. An applicator for the purposes described comprising a mass of material to be applied and fibrous retaining material embedded therein and substantially uniformly distributed therethrough, said fibrous material being of a nature to be removed gradually by the action of a movable finishing surface when the applicator is pressed thereagainst to apply the first named material, and said material being of sufficient rigidity to prevent collapse of the mass when pressed against the finishing surface with sufficient pressure to apply said first named material.

2. An applicator for applying material of the character described onto moving finishing surfaces comprising a mass of the material to be applied, a reinforcing material embedded therein, said reinforcing material being stronger than the material to be applied, and of a nature to be removed gradually by action of the finishing surface when the resultant mass is pressed thereagainst to apply the first named material, and said reinforcing material being removable from an article finished by the wheel by the same treatment that removes the material applied thereby.

3. An applicator for applying materials of the character described onto moving finishing surfaces comprising an elongated self-supporting body of laminated structure, and said laminations containing and retaining the material to be applied.

4. An applicator for applying materials of the character described onto moving finishing surfaces comprising a casing, a cellular core within the casing, the cells thereof being substantially uncommunicated from each other, and material to be applied onto the finishing surface disposed within and retained within said cells.

5. An applicator for applying materials of the character described onto moving finishing surfaces comprising a sheathing, a core therein, said core having a plurality of elongated longitudinally extending cells and material to be applied disposed within said cells and reinforced by the walls thereof.

6. An applicator for applying materials of the character described onto moving finishing surfaces comprising an elongated self-supporting cellular body and material to be applied contained in said cells and permeating the body material.

7. An applicator for applying materials of the character described onto moving finishing surfaces comprising absorbent reinforcing material, material to be applied, distributed therethrough and retained thereby in a predetermined shape, and said resultant reinforced mass having sufficient rigidity to withstand axial collapse when held against the moving finishing surface with sufficient pressure to cause the materials to rub off onto the surface.

8. An applicator for applying materials of the character described onto moving finishing surfaces, comprising a sheet of self-supporting material wrapped in spiral convolutions, wall portions of adjacent convolutions of the spiral being spaced apart from each other, and material to be applied contained between said spaced wall portions.

9. An applicator for applying materials of the character described onto moving finishing surfaces comprising a spirally wrapped sheet of self-supporting material, wall portions of ad-

5 jacent turns of the spiral being spaced apart from each other, material to be applied retained between said spaced wall portions, and reinforcing means between the adjacent turns of the spirally wrapped sheet dividing the resultant spiral laminations into a multiplicity of longitudinally extending pipes.

- 10 10. An applicator for the purposes described comprising a spirally rolled sheet of corrugated paper with spaced wall portions of adjacent turns of the resultant spiral in contact with each other, whereby the corrugations form a plurality of longitudinally extending pipes, and material to be applied contained in said pipes.
- 15 11. An applicator for applying materials of the character described onto moving finishing surfaces comprising a corrugated paper sheet, a

backing sheet secured thereto and maintaining the corrugations in the first sheet, layers of said combination sheet being superimposed with the corrugations extending longitudinally of the resultant structure, and material to be applied received and retained in the spaces between said sheets.

12. An applicator for applying materials of the character described onto moving finishing surfaces comprising a self-supporting casing, superimposed layers of corrugated sheet material secured therein with the corrugations extending longitudinally of the casing, and the spaces defined by said corrugations being filled with the material to be applied.
